TYPEWRITING MACHINE

William A. Dobson, Hartford, Conn., assignor to
Underwood Corporation, a corporation of Delaware

Application March 2, 1944, Serial No. 524,788

2 Claims. (Cl. 197—70)

This invention relates to margin gaging mechanism for typewriters and the like machines, of the kind in which the margin stops are selectively positionable along a supporting rack.

An object of the invention is to provide an improved margin gaging mechanism particularly suitable for typewriters of the portable class.

A further object is to provide an improved construction of the margin stop unit to afford economic fabrication and finger-release manipulation in positioning the stop selectively on its supporting rack.

Other objects will be in part pointed out and in part obvious as the following description of the preferred embodiment of the invention proceeds.

In the drawing,

Figure 1 is a front elevational view of the related portions of a typewriter embodying the invention, portions being broken away to facilitate illustration;

Figure 2 is a transverse sectional view taken on line 2—2 of Figure 1, and

Figure 3 is a fragmentary perspective view of the improved margin stop, shown in released condition on the supporting rack.

The invention, as illustrated, is embodied in an Underwood typewriter of the portable class comprising a main frame, of which side members 5 are shown, and a carriage 6 supporting a platen 7 and arranged for line typing and return travel on the main frame, in the usual manner. A bracket plate 8 is secured at each end to the main-frame members 5 and provides support for a line-end signal device 9 and a margin-gaging counterstop 10. The construction and operation of devices 9 and 10 is more fully shown and described in my Patent No. 2,328,375, issued August 31, 1943. For the purposes of the present invention it will suffice to note that the signal device 9 and the counterstop 10 cooperate with left and right margin stops 11, 12 on the carriage, in the well known manner. As disclosed in said patent, the counterstop 10 is arranged for pivotal limited movement leftward to operate line locking devices, and is arranged for downward retractive movement clear of the stops 11, 12, to effect margin release. Counterstop 10 is urged upward and rightward to its normal position by a spring 13.

The platen carriage 6 is of the conventional construction comprising end members 15 on which the platen 7 is rotatably supported, and a paper table or rest 16 rigidly secured by screws 17 to the carriage. The paper table 16 has end

walls 18 through which the screws pass for threading engagement into the end members, spacer collars 19 being interposed between the connecting parts. The paper table also includes 5 an inclined front wall 20 and an upright rear wall 21, all said walls preferably forming a one-piece, integral hollow structure affording a housing or mask for the margin stops and supporting rack now to be described. An apron 22 extends 10 around the lower part of the platen 7, issuing upwardly and rearwardly substantially contiguous with the paper table 16, to afford a guide surface facilitating the insertion and feeding of a work sheet into the machine.

15 The stop rack is indicated at 23 and embodies an elongate bar secured at each end to the carriage-end members 15 and having at its front face a series of notches at letter-space pitch. The stops 11 and 12 are similar in construction 20 and therefore a description of the left margin stop, Figure 3, will suffice. The stop 11 includes a body portion 24, presenting a top 25 the ends of which are bent down to form, respectively, a front 25 panel 26 and a back panel or finger piece 27, the latter being recessed or concave to fit the finger. At each side edge the finger piece 27 is extended 30 forwardly to form side walls 28 cut out at 29 to fit against the bottom face of the rack 23, with the top 25 lying against its upper face. The front panel 26 is reinforced by a backing plate 30 secured thereto and has at each side edge a tooth or prong 31 projecting rearwardly, the two prongs being spaced so as to each enter a notch 35 of the rack bar. The lower edge of the front wall 35 provides an upright shoulder 32 and an inclined face 33. The shoulders 32 of the two stops 11, 12 confront each other and the two faces 33 are oppositely inclined.

40 Between the side walls 28 of the stop is slidably arranged a U-shaped shoe 34 having side flanges slidably contacting the side walls, these flanges being bent off at their top edges to form guide lugs 35 each fitting slidably between the top edge of a side wall 28 and the top panel 25. The intermediate member of the shoe 34 has a pin bent therefrom to form a guide for a compression spring 36 pressing against the wall 27 of the body portion. The spring 36, pressing the 45 shoe 34 against the rack, urges the body 24 of the stop rearwardly so as to press the two prongs 31 into the rack notches. Manual pressure on the finger piece 27, against the force of spring 36, moves the body 24 of the stop forward and thus 50 withdraws the prongs 31 from the rack notches,

as shown in Fig. 3, so that the margin stop may be slid along the rack to the desired position. As the stop is released, the side flanges of shoe 34 keep the stop from canting sideways. The finger pressure may be strong, to the extent that the vertical edges of the cut outs 29 engage the rear face of the rack, these edges thus acting as a gage to assure that the prongs 31 are clear of the rack teeth. As the margin stop is moved along the rack, the shoe 34, having broad contact with both the rack and the interior sides of the stop, keeps the stop at right angles to the rack, thereby avoiding having the prongs 31 catch in the rack notches while the stop is being moved. Upon release of finger pressure spring 36 causes the prongs 31 to seat in other notches of the rack to lock the margin stop in the new position.

As shown best in Figure 2, the rack 23 is arranged beneath the paper table 16, well within the angle defined by the front and rear walls 20, 21 thereof, so that the rack and the stops thereon are concealed from casual view. The body portion 24 of each stop extends rearwardly from the rack to project through an opening 39 in the rear wall of the paper table, to make the finger piece 27 easily accessible to the operator's fingers reaching over the paper table. Each margin stop 11, 12 carries a pointer 38 which preferably is formed of an extension of the top member 25 of the stop. In the front wall 20 an elongate opening 40 is provided through which the ends of the pointers 38 are visible. This opening may have a transparent covering or window 41 on which a scale calibrated in letter spaces and inches is arranged.

In use a work sheet may first be placed around the platen in the usual manner, however without particular care as to its exact lateral location. Allowing the trailing portion of the sheet to hang over the platen, instead of letting it rest on the

paper table, the stop pointers and scale are in view and the margin stops 11, 12 may be moved to their desired locations as gaged from the side edges of the sheet. If margins of exact measure are desired, the bend of the work sheet may be held close to the window and each margin may be measured along the scale, from the adjacent work-sheet edge. If a typing line of a certain length or a certain number of letter spaces is required, the stop pointers may be positioned directly at the appropriate calibrations on the scale.

What is claimed is:

1. In a typewriter, a stop unit adapted for position adjustment and locking engagement on a toothed rack, comprising a box-like body portion formed of sheet metal and including a top panel, end panels bent off from the top panel and side panels bent off from at least one end panel and defining aligned openings admitting the rack, the body portion being substantially longer than the width of the rack to afford a rectangular recess adjacent one side of the rack, and a shoe slidably fitting the recess and spring-pressed into contact with the rack.
2. In a typewriter, a stop unit adapted for position adjustment and locking engagement on a toothed rack, comprising a box-like body portion formed of sheet metal and including a top panel, end panels bent off from the top panel and side panels bent off from at least one end panel and defining aligned openings admitting the rack, the body portion being substantially longer than the width of the rack to afford a rectangular recess adjacent one side of the rack, and a U-shaped sheet metal shoe slidably fitting the recess, with its sides contacting a substantial length of the side panels.

WILLIAM A. DOBSON.
